CORNER TRUING TOOL

Thomas C. Kennedy, Chicago, Ill.

Application June 3, 1946, Serial No. 673,957

5 Claims. (Cl. 33—85)

1

This invention relates to corner truing tools, and its principal object is to enable bricklayers, carpenters and erectors to true up the corners of many sided chimneys or corners of other surfaces and upright building structures.

Some chimneys taper more or less from their bases to their upper ends, and tools have been provided for truing up the sides or surfaces of chimneys and structures after one or more courses have been laid, and while the mortar is still soft, or where a timber or metal surface is erected.

With the present tool, both sides forming a corner of a structure of square, octagonal, circular or other configuration, are trued up with one operation. The former practice was performed by plumbing first one surface and then the other surface of the corner, requiring two separate operations of the mechanics to keep the corner line straight and plumb.

Another object is to provide a tool of this character, which may be used to level up courses of brick or other masonry, carpentry work or structural metal or piping, with one movement of the mechanic.

With these and other objects and advantages in view, this invention consists in the several novel features hereinafter fully set forth, and more particularly defined in the appended claims.

The invention is clearly illustrated in the drawing accompanying this specification in which:

Fig. 1 is a side elevation of a corner truing and leveling tool, embodying a simple form of the present invention;

Fig. 2 is a front elevation of the tool seen in Fig. 1;

Fig. 3 is an end view thereof;

Fig. 4 is an end view of a slightly modified form of the tool, and

Fig. 5 is a perspective view of a clip for holding a spirit level.

Referring to said drawing, and first to Figs. 1 to 3 inclusive, the reference characters 10, 10, designate two similar gage members, desirably formed of elongated strips of sheet metal bent up to provide two parallel spaced webs 11, from which project oppositely directed aligned flanges 12. The webs 11 are also bent up to form oppositely directed webs 13, which terminate in parallel flanges 14. The flanges 12 and webs 13, extend at an angle of 90 degrees to the webs 11, and the flanges 14 extend at an angle of 90 degrees to the webs 13. The corners 9, formed by the webs 11, 13, cooperate with the edges 8, of the flanges 14, to true up the adjacent sides of

corner bricks of chimneys or buildings, and other structures and timbers.

The widths of the webs 13 and flanges 14, are so proportioned that when corners 9 and the edges 8 of the flanges 14, are placed against the bricks or timber at a corner of a chimney or surface of other structure, with the corner line of the chimney midway between the corners 9 of the tool, the user can true up the corner and observe with certainty whether the corner is true, and whether the faces of the structure adjacent thereto extend at the proper angle of inclination.

The flanges 12, and webs 11, provide a hand-holding surface or a handle by which the tool is manipulated. The handle portion may be slightly shorter than the remainder of the tool for inspection of corners.

Between the webs 11 is one or more spacers 15, which space the two gage members apart. The webs 11, and spacer 15, are secured together by rivets, screws or the like 16.

Tiltably mounted on one or both ends of the handle is or are spirit levels, one of which is seen at 17, each of which is secured in a U-shaped clip 18, frictionally held between the webs 11, as by a screw 19, said clip having perforated arms 18a, which extend beyond the webs 11, and over the rounded ends of the spirit level and secure the same in place. By partially unscrewing the screw 19, the clip may be tilted to any desired angle of inclination, and that angle determines the slope or taper of the walls of the chimney or other structure.

When the spirit level is set at right angles or 90 degrees to the tool, then when the latter is placed against the corner or faces of a wall, the spirit level indicates that the wall is plumb.

In Fig. 1, the dotted line X indicates a vertical line, and the tool is shown as held at a definite angle to said vertical line, which angle determines the slope of the side walls of the chimney or other structure.

The flanges 12, and webs 11, are notched out as at 21, to receive another adjustable spirit level 22, which is also held in place by a U-shaped clip 23, similar to the clip 18, permanently but adjustably held in place parallel with the length of the tool by a screw 23a.

In use, after a course of bricks has been laid in mortar, the tool may be used as a horizontal level to determine if the bricks are laid level. The spirit level 17 and clip 18 are adjusted to the required angle of inclination to give the desired slope to the walls or surface of the chimney or

other structure. At the corners of the chimney, or other structure, the corners 9, and the edges 8, of the tool are placed against the corner surface of a few courses of the corner bricks, with the corners automatically located by the tool exactly midway between the sides of the slot between the webs 11. If some of the bricks at the corner are not in true alignment, they may be adjusted manually to bring the sides thereof against the corners 9 and edges 8, with the corners of the bricks disposed midway in the slot.

In the form of the invention illustrated in Figs. 1 to 3 inclusive, the tool has been designed for truing up square corners, as indicated by the dotted line 24.

In the form of the invention illustrated in Fig. 4, the proportions of the webs 13a and flanges 14a have been varied so as to adapt the tool for truing up the corners of octagonal chimneys or other structures, as indicated by the dotted line 25.

With the use of the present tool, the workman can true up a few courses of a corner in one operation, thereby saving half the time of truing up the two adjacent corner faces of any structure by two operations, as is now required. It is understood that in erecting a chimney, or building or structure, after one or more courses of the corner bricks have been laid, guide lines may be fastened to the corner bricks to aid the workman in laying the bricks straight between the corner bricks.

It is further to be observed that the webs 13 and flanges 14, provide a channel shaped gage for indicating the trueness of corners.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. A corner truing tool comprising two similar frame members having parallel flanges from which extend aligned webs that terminate in parallel webs, said first mentioned webs and flanges forming a channel shaped gage, spacers secured between the parallel webs and spacing the frame members apart, and a tilttable spirit level adjustably secured upon one end of the parallel webs and extending along the end thereof.

2. A corner truing tool comprising a frame composed of two similarly shaped pieces, each formed with a web from which extends a flange and another web which terminates in a flange, said webs and said second named flanges providing a channel shaped gage, the first named flanges, together with the first named webs, forming a handle, a tilttable clip adjustably secured

on one end of the handle, and a spirit level secured in said clip and extending along the end of said webs.

3. A corner truing tool comprising a sheet metal frame composed of two aligned spaced webs, the outer edges of which terminate in two spaced parallel flanges adapted to straddle the corner portion of an object with the corner entering the space between the webs, other parallel webs extending from the aligned webs at the inner edges thereof and terminating in aligned flanges, spacers secured between the second named webs, and a tilttable spirit level secured at one end of the second named webs.

4. In a corner truing tool for masonry, a base portion, a pair of longitudinally extending, oppositely disposed, L-shaped members carried by the base portion, each having one of their corresponding legs positioned in substantially a common plane, and the other respective legs extending in the same direction and lying in substantially parallel planes, the opposing longitudinal edges of said first-mentioned legs being spaced from one another to receive the juncture of two intersecting wall surfaces, with said spaced edges and the free edges of the other legs engageable with such surfaces for firmly seating the device thereon, and a spirit level carried by said base portion for indicating the relationship of said L-shaped members to the horizontal.

5. In a corner truing tool for masonry, a frame comprising two similarly shaped sheet metal pieces having spaced longitudinally extending, opposed base portions, means for securing the latter together, said portions each terminating at one of their corresponding longitudinal edges in an outwardly extending web, with the respective webs lying substantially in a common plane, each free longitudinal edge of the respective web portions terminating in a flange positioned on the opposite side of such web relative to its respective base portion, the free longitudinal edges of the respective flanges and the junctures of the webs with their respective base portions extending substantially parallel to one another and providing a pair of spaced edges for each base portion, said edges of each pair being engageable with one of a pair of intersecting surfaces for seating the device thereon, and a spirit level supported by said base portions for indicating the relationship of said pairs of edges to the horizontal.

THOMAS C. KENNEDY.
